BY *William J. Fausten*
ATTORNEY.

UNITED STATES PATENT OFFICE.

GEORGE W. DEEDS, OF PHILADELPHIA, PENNSYLVANIA.

SASH LOCK.

1,418,290.

Specification of Letters Patent. Patented June 6, 1922.

Application filed October 21, 1920. Serial No. 418,554.

To all whom it may concern:

Be it known that I, GEORGE W. DEEDS, a citizen of the United States, residing at the city of Philadelphia, county of Philadelphia, and State of Pennsylvania, have invented a certain new and useful Improved Sash Lock, of which the following is a specification.

This invention has relation to window-sash, sliding gates, doors and the like which may be locked upon the inside, while closed or in any one of a number of partly open positions, to prevent unlocking from the outside.

15 The leading object of the present invention is to provide a lock to be employed in this respect which is simple, practical, efficient and comparatively inexpensive to manufacture and which can only be unlocked by 20 means of a removable key insertible from one side of the lock casing. Other and further objects relate to the provision of general details of construction and in the novel arrangement, connection and combination of 25 parts as will hereinafter appear.

The invention consists of the improvements hereinafter described and finally claimed.

30 The nature, characteristic features and scope of the invention will be more fully understood from the following description taken in connection with the accompanying drawings forming part hereof, and in which:

35 Fig. 1, is a fragmentary view in front elevation of a window sash equipped with a lock embodying features of the invention.

Fig. 2, is a view in side elevation thereof.

40 Fig. 3, is a view in front elevation of the lock detached, the cover plate being removed for the sake of clearness.

Fig. 4, is a view thereof in cross-section.

Fig. 5, is a detached view in elevation of the longitudinally shiftable bolt shown in Figs. 3 and 4, and

45 Fig. 6, is a similar view of the vertically shiftable detent shown in Figs. 3 and 4.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise

arrangement and organization of the instrumentalities as herein shown and described.

For the sake of illustration I have shown 60 the lock applied to window-sash although obviously the same is applicable to sliding gates, doors and the like.

In the preferred form shown, 10 designates a casing having a removable cover 11 secured to the open side of said casing. The closed side of the casing is presented for instance to the lower sash frame 12 of a window, screws 13 being employed for securing said casing to place. Located within 70 said casing are elongated, parallel plates 14 and 15 of which plate 14 is longitudinally shiftable and plate 15 is vertically shiftable. Pins 16 extend laterally across the casing for guiding said plates, plate 14 being horizontally slotted as at 17 and plate 15 being vertically slotted as at 18 to permit such movement of said plates. Plate 14 is interlocked with respect to plate 15 at the extreme 75 shifted positions thereof. For this purpose 80 a lug 19 extends laterally from the rear face of plate 14 and is adapted to engage one or the other of the notches 20—21 of slot 22 in plate 15. A leaf spring 23 interposed between the casing top and the upper faces of 85 said plates serves to normally maintain said plates in proper position. The under faces of plates 14—15 are cut away as at 24 and 25 respectively so that when a conventional key (indicated by dash-lines in Fig. 3) is 90 inserted through key-hole 26 in the casing cover and moved toward the right in Fig. 3, said key engages the cut-away surface 25 of plate 15, lifts the latter against spring 23 thereby causing lug 19 to be disengaged 95 from notch 20 so that slot 22 comes into alignment with said lug. Further movement of the key causes it to impinge against the underside of plate 14 and shift it toward the right in said figure so that the notched 100 end 27 thereof enters the groove 28 of a laterally disposed detent 29. During this movement lug 19 has come into alignment with notch 21 whereupon plate 15 returns to normal position under pressure of spring 105 23 and detent 29 is locked in place. This detent passes through casing 10 including its cover, through the lower sash frame and engages one of several sockets 30 in the upper sash frame. The detent 29 is provided with 110 a knob 31 so that it may be readily disengaged from a socket 30 when the plate 14

is in the position shown in Fig. 3. The plate 14 is shifted to such position by inserting a key in said casing and moving the same toward the left in said figure. The detent 29 interlocks the sash frame and the latter is detained by plate 14. Since plate 14 can only be shifted by a conventional key insertible in casing 10 obviously it is impossible for an unauthorized person to open said window-sash either from the inside or outside.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the

invention or sacrificing any of its advantages.

What I claim is:

A lock comprising a housing, parallel plates slidably mounted therein of which one is longitudinally movable and the other vertically movable, the under faces of said plates being cut-away, a transversely mounted detent extended through said housing having a notched portion with which the longitudinally shiftable plate is adapted to engage, a key for co-operatively engaging the cut-away portion of said plates for shifting them, means arranged between said plates for interlocking them and a spring interposed between the top of the vertically movable plate and the top of said housing for normally maintaining said plates in the same horizontal plane.

In testimony whereof, I have hereunto signed my name.

GEORGE W. DEEDS.
